UNITED STATES PATENT OFFICE.

FRANK G. BURGHOFFER, OF BELLINGHAM, WASHINGTON.

GAS-ENGINE GOVERNOR.

1,072,696.

Specification of Letters Patent.

Patented Sept. 9, 1913.

Application filed August 28, 1912. Serial No. 717,557.

To all whom it may concern:

Be it known that I, FRANK G. BURGHOFFER, a citizen of the United States, residing at Bellingham, in the county of 5 Whatcom and State of Washington, have invented new and useful Improvements in Gas-Engine Governors, of which the following is a specification.

This invention provides a governor mechanism for internal combustion engines, the 10 same being adapted most especially for engines of this type of the two-cycle variety which require a close adjustment of the timer and throttle in order to maintain a 15 uniform speed.

The governor mechanism devised in accordance with this invention admits of the timer and throttle to be operated automatically or independently by hand so that when 20 starting the engine the governor may be thrown out of action and after the engine has been gotten under headway the governor mechanism may be thrown into operation to regulate the spark and the throttle 25 according to the speed and load.

The invention consists of the novel features, details of construction and combination of parts, which hereinafter will be more particularly set forth, illustrated in the accompanying drawing, and pointed out in 30 the appended claims.

Referring to the drawing, forming a part 35 of the specification, Figure 1 is a perspective view of a governor mechanism for internal combustion engines embodying the invention. Fig. 2 is a detail view of the timer shaft and the sleeve splined thereon, together with portions of the throttle shaft and sleeve mounted thereon and the connecting 40 means for transmitting power from the sleeve splined to the timer shaft to the throttle shaft.

Corresponding and like parts are referred 45 to in the following description, and indicated in all the views of the drawing, by the same reference characters.

The shaft 1, designated as the timer shaft, 50 may also constitute the shaft of the governor and is adapted to be driven in any manner from a rotating part of the engine, a bevel gear 2 being provided for this purpose and secured to the shaft 1. A timer 3, such as 55 generally provided for internal combustion engines utilizing an electric ignition system, is loose upon the shaft 1 to be moved for advancing or retarding the spark. A

sleeve 4 splined upon the shaft 1 has upper and lower disks 5 and 6. Governor arms 7 have their upper ends pivoted to a cross-head 8 secured to the shaft 1, whereas their 60 lower ends are pivoted to a crosshead 9 secured to the sleeve 4. The governor arms 7 are weighted in the usual manner. When the shaft 1 is driven at a high speed the weighted portions of the governor arms 7 65 move outwardly, thereby moving the sleeve 4 upward upon the shaft 1, but when the speed of the shaft 1 decreases the sleeve 4 is lowered by the weighted portions of the governor arms moving inwardly. A shaft 70 10 mounted in a bearing 11 has a wheel 12 at one end to enter the space formed between the disks 5 and 6 so as to make positive engagement with one or the other of said disks according to the position of the 75 sleeve. A pinion 13, fastened to the opposite end of the shaft 10, meshes with a gear wheel 14 secured to a shaft 15, which is arranged parallel with the shaft 1. The wheel 12 is preferably of the friction type to engage 80 frictionally with the disks 5 and 6.

A hollow shaft 16 is mounted upon the shaft 15 and is loose thereon. An arm 17 fastened to the shaft 16 is adapted to be connected with the throttle of the engine by 85 means of a rod 18. A second arm 19, secured to the shaft 16, is adapted to be connected with the shaft 15 so as to turn therewith and has connection with the timer 3 by means of a rod 20. A sector 21, secured to 90 the shaft 15, is adapted to be adjustably connected with the arm 19. For this purpose the sector 21 has a plurality of notches 22 and the arm 19 has a catch 23, which is adapted to be thrown into engagement with 95 any one of the notches 22 so as to form a lock between the sector 21 and the arm 19. When starting the engine the catch 23 is moved to release the sector 21 from the arm 19 so that the timer and throttle may be 100 operated by hand in the usual way. After the engine has been started and it is required to bring the governor mechanism into play the catch 23 is thrown into engagement with the sector 21, thereby locking the 105 shafts 15 and 16. When the speed of the engine is excessive the weighted ends of the governor arm 7 fly outward and elevate the sleeve 4, thereby bringing the lower disk 6 into engagement with the wheel 12 to turn 110 the shaft 10 and the shafts 15 and 16, with the result that the timer is moved to retard

the spark and the throttle is operated to reduce the supply of gaseous mixture to the engine. When the speed of the engine decreases the weighted portions of the governor arms 7 move inward and lower the sleeve 4, thereby bringing the disk 5 into engagement with the wheel 12 to rotate the shaft 10 in an opposite direction, together with the shafts 15 and 16, whereby the timer 10 is moved to advance the spark and the throttle operated to admit a greater supply of mixture to the engine, which latter picks up so as to run at the required speed for which the governor may be set.

15 From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that 20 the device shown is merely illustrative, and that such changes may be made when desired as are within the scope of the claims 25 appended hereto.

Having thus described the invention what 30 is claimed as new, is:—

1. In a governor mechanism for internal combustion engines, the combination of concentric shafts, one of said shafts being adapted to have connection with the timer 35 and the throttle of the engine, connecting means between the two shafts to admit of one being moved independently of the other

or both being connected at any relative adjustment for simultaneous movement, a shaft adapted to be operated from a moving part 40 of the engine, governor arms secured at one end to said shaft, a sleeve splined to the shaft and having the opposite ends of the governor arms connected thereto, a shaft 45 geared to one of the concentric shafts, and a wheel secured to the last mentioned shaft and arranged to operate between the disks of the before mentioned sleeve.

2. A governor mechanism for internal combustion engines comprising a power operated shaft adapted to be driven from a moving part of the engine, a timer loose on said shaft, a sleeve splined to the shaft, governor arms connecting said sleeve and shaft, concentric shafts parallel with the power driven shaft, an intermediate shaft geared to one of the concentric shafts, a wheel secured to the intermediate shaft and arranged to operate between projecting portions of the before mentioned sleeve, connecting means 60 between the other one of the concentric shafts and the timer and throttle of the engine, and connecting means between the said concentric shafts to admit of connecting them in any relative adjusted position or to 65 admit of said shafts having independent movement.

In testimony whereof I affix my signature in presence of two witnesses.

FRANK G. BURGHOFFER.
